UNITED STATES PATENT OFFICE

2,580,779

PHOTOGRAPHIC PROCESSING APPARATUS

Eric H. Heyer, Los Angeles, and Edward Z. Walters, North Hollywood, Calif.

Application December 16, 1947, Serial No. 792,016

13 Claims. (Cl. 95—73)

1

This invention relates to automatic equipment, and particularly to a completely automatic roll film negative developing, printing, and print developing machine which requires only that the roll film be inserted by hand and the completed prints and negatives be removed by hand from a special depository. All other operations are controlled and performed automatically.

Photographic units in the form of cameras having developing units attached thereto are known, as well as automatic developing units for film, such as motion picture film, the latter having been used to a considerable extent. The present invention, however, is directed to a complete continuous unit which not only develops a roll of negative film, but prints the negatives to paper, controls the printing operation in accordance with the density of the negative, finally develops the prints, and then deposits them in a container to which access may be had only by the holder of a proper key obtained at the time the film is first started through the machine.

The general operations on the film, after the spool has been inserted in a spool holder similar to a spool holder in a camera, and after the end of the paper backing roll has been inserted in a spring operated clip which separates the paper from the film, are the attachment of the film to a developing belt, which passes the film negative through the various film processing solutions and through a film dryer, the separation thereof from the belt, the presentation of the negative to an automatic printer where it is printed to paper stock according to the density of the negatives, the attachment of the paper stock to a print processing belt where the stock is processed and dried, the separation of the stock from the belt, the depositing thereof in a container, and the bypassing of the print processing tank by the negative film for delivery to the print container. To obtain access to the starting point of the mechanism where the film is inserted, a coin must be deposited, at which time a key is obtained for the container to which the film will be delivered. The entire process has been designed to take approximately thirty (30) minutes or less, from the time the film enters the machine until it enters the final depository. In this manner, the usual time element required for obtaining a complete set of prints from a roll of negative film is very much shortened, particularly when the usual practice is to deliver film to a drug store or other photographic shop where the general time minimum for obtaining the prints is about 24 hours.

2

The principal object of the invention, therefore, is to facilitate the continuous process of development of a roll of negative film, the printing of the negatives to print stock, and the developing of the print stock.

Another object of the invention is to provide a completely automatic roll film developing, printing, and print processing machine.

A further object of the invention is to provide an improved continuous and automatic negative film developing process and equipment in combination with an automatic printer for the negative and an automatic print processing method and equipment.

15. A still further object of the invention is to provide a coin-operated roll film developing and printing and print processing system including a safety depository for the negative and prints.

Although the novel features which are believed to be characteristic of this invention will be pointed out with particularity in the appended claims, the manner of its organization and the mode of its operation will be better understood by referring to the following description read in conjunction with the accompanying drawings, forming a part hereof, in which:

Fig. 1 is a front elevational view of a complete automatic machine embodying the invention.

30. Fig. 2 is a perspective view of the end of the unit at which the film is entered.

Fig. 3 is a perspective view of the end of the unit at which the developed negative and prints therefrom are obtained.

35. Fig. 4 is an enlarged elevational view of the negative developing equipment and the automatic printer portion of the machine.

Fig. 5 is a detailed view of the unit for fastening the negative to the negative processing belt and the print stock to the print stock processing belt.

40. Fig. 6 is an enlarged elevational view of the print processing, drying, and delivering unit for the print stock.

Fig. 7 is a detailed view of the paper starting, stopping, and cut-off mechanism.

Fig. 8 is an end view of the depository for the finished prints and negatives, and

Fig. 9 is a perspective view of a key used in the invention.

Referring now to the drawings, in which the same numerals identify like elements, the entire equipment is enclosed in a light-tight housing 5 having a hinged door 6 for the entrance of the film and a circular opening through which the

end of a cylindrical depository 1 protrudes. Referring particularly to Fig. 4, the door 6 is hinged at 9, biased toward open position by a spring 10, and adapted to close a microswitch 11 when the door is in closed position. The closed microswitch 11 also energizes a solenoid 14 which holds a latch 15 in locked engagement with a latch 16 on the door to maintain the door closed while the film is being removed from its spool. Positioned below the door is a coin-operated unit 20 having a handle 21, a coin slot 22, and a key receiving tray 23. The operating circuit for the motors and other equipment passes through the microswitch 11 and the coin box 20 so that it is necessary for both the door 6 to be closed and a coin to be inserted in the slot 22 before the equipment will function.

To start a film in the system, the roll of film, after exposure in a camera, is placed between the ends of spool holding brackets 26, as shown at 27. The backing paper is then partially removed and the end attached to one of the clamps such as shown at 29 on a drum 30. After the door 6 is closed and the coin inserted and the handle 21 pushed down, the drum 30 will revolve 180°, and because of the curl in the film, its loose end will enter channel chute 32 between driven rollers 33. When the end of the film is reached, it will be torn from the paper, the paper continuing around the drum 30 to be deposited in a basket 35 when the clip 29 contacts a release cam 31 which releases the paper from the clip. The paper is held flat on the drum by a pressure plate 34.

When the forward end of the film, as shown at 44 (see Fig. 5) reaches the end of the chute 32, it will pass between a belt 36 and a roller 37, thus moving a rod 38 to the left so that a spring biased latch 39 passes to the left of a second spring biased latch 40, the latch 40 maintaining an electrical contact 42 open until it is moved to the right. The film 44 continues along with the belt 36 until it reaches a microswitch roller 45 which it moves to the left, closing an electrical circuit through a solenoid 46 energized from a source of energy, such as shown at 47. Actuation of the solenoid 46 first moves the housing 48 to the right until it contacts the film and a staple is then driven, by further plunger action, through the film and into the belt 36, a backing plate 49 being provided. The stapling device is of the magazine type holding a U-shaped clip of wire staples well-known in the art. The movable plunger within the coil 46 pushes a staple from the magazine, which is in the vertical arm of the housing 48, through the film 44 into the belt 36, similarly to the action of the well-known Hotchkiss or Bates office staples. The function of the backing plate is to slightly bend over the ends of the wire staple. When the tail end of the film passes the roller 37, it is moved to the right by a spring 41 against the belt 36, thus actuating latch 40 to close contact 42 which again energizes solenoid 46 to staple the rear end of the film to the belt 36. The closing of the contact 42 also breaks the energizing circuit of solenoid 14, allowing spring 10 to open the door 6 to indicate that the machine is ready for the insertion of another roll of film.

Referring again to Fig. 4, the negative is then carried by the belt 36 through the various processing tanks, such as a developing tank 53, a short stop tank 54, a hypo tank 55, and a washing tank 56, the film then passing into a dry box 58 having a plurality of drying lights 59. The dry box is also

provided with a motor driven fan 61 which will circulate air from the bottom of the box through the top of the box, as indicated by the arrows.

When the forward end of the film reaches a roller 62, a separator in the form of a blade 63 passes between the film and belt to remove the staple, thus permitting the film to pass between drive rollers 65 and into a channel chute 66. It will be noted that, when the film is unwound from the spool 27, the emulsion side faces downwardly and is attached to the belt with the emulsion side out. Stapling by stapler 48 is done slightly back of the forward end of the film, this distance being that between the stapler 48 and the roller 45. Thus, the front end of the film bends slightly away from the belt 36, permitting the separator blade 63 to be inserted between the film and belt, and thus, insure the separation of the film from the belt.

20 The film then continues through the chute 66, and, after passing drive rollers 67, is superimposed upon print stock from a roll 69 at point 70. However, before the film reaches point 70, it passes between a light source 72 and a photoelectric cell 73, the latter being connected to a solenoid potentiometer 75 which varies the energy from a source 76 over conductors 77 to a printing light source 78. A shutter device controlled by the cell 73, such as shown in U. S. Patent No. 1,925,355, could also be used. In this manner, each negative is measured for density, and the printing light automatically adjusted to provide the proper exposure of the paper stock.

30 The printer also includes a condenser and diffusing lens unit 81, a slit plate 82 with narrow printing aperture 83 therein, the plate being held by spring tensioned members 85. By the use of a narrow printing aperture, the film and paper may be advanced continuously past the light source, the light intensity being varied to provide the proper exposure.

35 To show the paper starting, stopping, and cut-off mechanism, reference is made to Fig. 7, wherein a microswitch 130 is closed by the forward end of the negative. This action energizes a solenoid 131 through a power source, such as a battery 132. Actuation of the solenoid presses a drive roller 135 on the negative 44 with sufficient force to permit the drive roller 136 to advance the paper in contact with the negative. When the front end of the negative reaches a roller 137, it readies a latching device, such as shown at 37-40 in Fig. 5. Thus, when the rear-end of the film passes roller 137, a contact is made to energize a solenoid 138 which lowers a knife 140 on the paper to sever it. When the rear end of the negative passes microswitch 130, the roller 135 will be raised, but the paper and negative will continue to be advanced by drive rollers 93 and 91, respectively.

40 Referring now to Fig. 6, after the printing operation, the film and paper are separated by the lower section 88 of film chute 89, (see Fig. 4) the negative being advanced by rollers 91 and 92 to depository 1. The paper is advanced into chute 94 by drive rollers 93 and to a print processing belt 95 where a roller 96 is moved to the left similarly to roller 37 in Fig. 5. The stapling unit 98 operates in the same manner as the unit shown in Fig. 5, except that the rollers 37 and 46 are reversed, since the paper and belt move upwardly. When the paper is stapled to the belt, it continues through the print processing unit 100 with its drive rollers 101 and idler rollers 102 and respective developing, fixing, and washing

tanks in the well-known manner, a preferred processing unit for paper stock being disclosed and claimed in copending application, Ser. No. 780,914, filed October 20, 1947.

After processing, the paper passes around a rotary drum dryer 105 having external drying lamps 107 and internal radiating heat units 108. After drying, the paper print is stripped from belt 95 by a separator blade 110, similar to the blade 63 in Fig. 4. The paper then continues in chute 111 to the depository 7. The speed of the negative through chute 89 and the speed of the print stock through unit 100 may be such that both reach the depository at substantially the same time. Thus, a contact arm having a roller 113 will move a latch 114 behind a latch 115 when the film and paper are passing into one of the containers such as shown at 118 in Fig. 8 of depository 7. When the rear end of either the paper or negative, whichever is last, passes the roller 113, however, a contact 119 will be made to energize a motor 121 from power source 122, which will rotate the depository through an angle of one container and then stop to present an empty container to the chute 111. Now, when a key 125, such as shown in Fig. 9, is inserted in its proper lock 126 according to its identification mark, the holder of the key may obtain the negative and prints in the container. The owner of the key does not have to immediately open his container, since the depository is large enough to accommodate a day's operation at the end of which an attendant will remove all films and package them for the owners, or deposit them in a storage depository with locks such as 126. The key 126 may be made to be unremovable after it has unlocked its container.

The above fully automatic roll film developer, printer, and print processor will, therefore, provide prints of a roll within less than one-half of an hour, or at any time the owner wishes to call for them thereafter. It is to be understood that certain features may be constructed differently from that described above without altering the function of the machine or departing from the scope of the invention.

We claim:

1. An automatic photographic continuous developing and printing machine for a roll of negative film on a spool comprising a serially arranged negative developer unit, a drying unit for said negative, a printing unit, a paper print stock developer unit, a drying unit for said paper print stock, an individual single loop belt carrier for said negative passing through said negative developer unit and said drier unit for said negative, an individual single loop belt carrier for said paper print stock passing through said print stock developer unit and said drying unit, means for separating rolls of exposed but undeveloped negatives of varying widths and lengths from their respective paper backings, mechanical means for automatically and physically attaching said undeveloped negatives to said negative developing belt carrier upon contact of said negatives with said means, wedge means for passing between said carrier and negatives for physically separating said negatives from said carrier after development and drying of said negatives, means for advancing paper print stock in contact with the developed negatives, and mechanical means for automatically and physically attaching said exposed print stock to said print stock developing belt carrier, wedge means for passing between said print stock and said car-

rier for physically separating said print stock from its carrier after development and drying of said stock, and means for delivering both said print stock and negative to a common point.

5 2. An automatic photographic developing and printing machine in accordance with claim 1, in which said first mentioned means includes a drum to which said backing paper is manually attached, rotation of said drum pulling said paper and separating said negative therefrom and advancing the end of said negative to said negative developing belt carrier.

10 3. An automatic photographic continuous developing and printing machine for a roll of negative film on a spool comprising a serially arranged negative developer unit, a printing unit, and a printing stock developing unit, each of said developing units having a single loop belt carrier, in combination with means for separating a roll of exposed but undeveloped negative from its interleaved paper backing, means for automatically attaching said undeveloped negative to said negative developing belt carrier with the emulsion side of said negative away from said belt carrier, wedge means for automatically separating said negative from its carrier after development of said negative, means for advancing paper print stock in contact with the developed negative, means for automatically attaching said exposed print stock to said print stock developing belt carrier with the emulsion side of said stock away from said belt carrier, wedge means for automatically separating said print stock from its carrier after development of said stock, means for delivering both print stock and negative to a common point, and a controlling means for said means for attaching said negative film to its carrier and said means for attaching said print stock to its carrier said controlling means including a plurality of electrical contact elements, means attached to said elements and movable by the beginning and end of said film to position and close said contacts, and a stapling device actuated by the closing of said contacts for stapling said negative to its carrier.

45 4. An automatic photographic developing and printing machine in accordance with claim 1, in which said wedge means for separating said negative film from its carrier and said means for separating said print stock from its carrier include a blade positioned for insertion between said negative film and its carrier, and a second blade positioned for insertion between said print stock and its carrier, the advancement of said negative carrier and negative directing said film toward said printing unit and the advancement of said print stock carrier and said print stock directing said print stock toward said common point.

50 5. An automatic photographic developing and printing machine in accordance with claim 1, in which said advancing means for said print stock in contact with said negative includes a drive roller, a pressure roller, means for positioning said print stock and negative between said rollers, electrical contact means actuated by contact with said negative, and means energized by the closing of said contact means for moving said pressure roller into contact with said negative.

55 6. In an automatic photographic continuous printing and developing machine, the combination of a negative film developing unit, a drier for said negative film, a roll of print paper from which different lengths may be severed, a light

source, means for continuously advancing said negative from said drier past said light source, a switch operative upon contact with said negative film, a pressure roller for pressing said negative in firm contact with said print paper, said pressure roller being actuated by said switch, for advancing said print paper in contact with said negative past said light source, and a second switch actuated in one direction upon contact with said negative film, and a cutter actuated by operation of said switch in the other direction by passage of the end of said negative print past said switch for severing a length of said print paper from said roll determined by the length of the negative film.

7. An automatic photographic printing and developing machine in accordance with claim 6, in which a second light source and a photoelectric cell are provided between which said negative film passes, and further means are provided for varying the intensity of the light from said first light source impressed on said negative in accordance with the density of said negative film as it passes said second light source.

8. In an automatic photographic printing and developing machine, the combination of a drum, a clamp on said drum to which the backing paper of a negative film roll is attached, means for advancing said drum to unroll said paper, a guide for the end of the negative film on said roll as said film is advanced and said paper is unwound from said roll, a single loop negative processing belting passing through a series of developing solutions, a stapling device adapted to staple each end of said negative to said belt for passage through said solutions, an automatic printer, a roll of print stock, said printer printing said negative to said print stock as said negative and print stock pass in contact through said printer, a single loop print processing belt, passing through a series of developing solutions for said print stock, a stapler for stapling both ends of said exposed print stock to said print processing belt for passage through said developing solutions, a depository having separated containers therein, a guide for directing said negative film to a container in said depository, means for advancing said print stock to said container in said depository, a motor for rotating said depository, and means operative by passage of said negative and print stock for energizing said motor to rotate said depository the width of one container.

9. An automatic roll film developer and printer comprising means to which the backing paper of a film roll is attached, drive means for rotating said means, a guide for directing the end of the negative film in said roll, said negative film being unwound by said first mentioned means, a single negative processing belt passing through a plurality of developing solutions, a stapler, means for actuating said stapler when the head end of said negative film reaches said processing belt, means for actuating said stapler when the tail end of said film reaches said processing belt, a continuous printer and print processing unit, said printer including a roll of print stock, means for advancing said print stock in contact with said negative film, means for automatically exposing said print stock to light in accordance with the density of said negative, and means for severing said print stock from said print stock roll, said processing unit including a series of

print stock developing solutions and a single belt passing through said solutions.

10. Automatic roll film apparatus comprising a unit for separating the backing paper from the negative film of a film roll, a negative film developing and drying unit, a single belt passing through said unit, a stapler, means for advancing said film to said stapler and said belt, means operative upon contact with said film for actuating said stapler for fastening said film to said belt, means adjacent said drier for separating said film from said belt, an automatic printer unit, a print developer unit, and a stapler unit, said printer including a pair of light sources, a roll of print stock from which different lengths may be severed, a photoelectric element receiving light from one of said sources through said film for controlling the intensity of said other light source, drive means for said print stock and film, and means for severing a length of said print stock determined by the length of said negative film, said print developer unit including a single belt passing through said unit, said stapler unit including means operative upon contact at the front end of said print stock for fastening said stock to said belt.

11. Automatic roll film apparatus in accordance with claim 10, in which a depository having individual containers therein is provided together with means for separating said stock from said belt, means for advancing said film from said printer unit to one of said containers, and means for advancing said stock to said same container.

12. Automatic roll film apparatus in accordance with claim 11, in which a motor is provided together with means actuated by the passage of said film and print stock into said container for energizing said motor for rotating said depository the width of one container.

13. Automatic roll film apparatus in accordance with claim 12, in which an enclosure is provided for housing all of said units, means being mounted externally of said enclosure for obtaining access to said unit for separating the backing paper from the film of said film roll.
